(57) **CLAIM**

The ornamental design for a holder for an electric toothbrush and a charger unit, as shown and described.

DESCRIPTION

FIG. 1 is a perspective view of a holder for an electric toothbrush and a charger unit from the top, front and left side, showing my new design;

FIG. 2 is a front view thereof;

FIG. 3 is a bottom plan view thereof;

FIG. 4 is a right side view thereof, the left side view being a mirror image thereof;

FIG. 5 is a top plan view thereof; and,

FIG. 6 is a rear view thereof.
